UNITED STATES PATENT OFFICE

EARL M. ALLEN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

APPARATUS FOR THE CONTROL OF RAILWAY SIGNALS

Application filed September 12, 1930. Serial No. 481,472.

This invention relates to apparatus for the control of highway signals at railway crossings. One of the objects of the invention is the provision of means whereby signal operating means responsive to approach of a train to a crossing may be readily cut out when a train for any reason stops in an approach section and whereby the signal control means may subsequently be restored 5 when the train proceeds. A further important object is to provide means whereby crossing signals may be set in operation when a train receding from the crossing reverses its direction of travel and proceeds toward 10 the crossing. The invention is particularly useful in congested territories where switching and train stops render desirable the suspension and resumption of crossing signal 15 operation. The invention further comprises 20 means whereby the manual control circuits may be restored to normal condition either manually or automatically. Other features of the invention will be hereinafter described and claimed.

25 The accompanying drawing consists of a diagrammatic view illustrative of my invention.

Referring to the drawing the reference character A designates a highway which 30 crosses a railway track X. Highway crossing signals 2, 2 of the usual type are connected in parallel as shown and are controlled by track sections on each side of the crossing. In the example illustrated the signals 2, 2, are 35 controlled by track sections 3, 4 and 5 on one side of the crossing and by sections 6, 7 and 8 extending on the other side of said crossing.

A relay 9 is controlled by track relays 10, 40 11, 12, connected to the respective track sections 3, 4 and 5. When none of said sections is occupied by a train said track relays are energized and a circuit through relay 9 is thereby established as follows: from terminal B of a battery or other source of electrical energy not shown in the drawing, through wire 13, armature 14 and front contact 15 of track relay 12, wire 16, armature 17 and front contact 18 of track relay 11, wire 19, armature 20 and front contact 21 of track relay 10, wire 22, relay 9, and wire 23

to the opposite terminal C of said source. When a train approaching the crossing from the left enters section 5, the track relay 12 is de-energized and the circuit through relay 9 is broken. Armature 24 of relay 9 then 55 engages back contact 25, thereby closing the circuit for operating the crossing signals 2, as follows: from terminal B, through back contact 26 and armature 27 of relay 28, wire 29, back contact 30 and armature 31 of relay 32, wire 33, back contact 25 and armature 24 of relay 9, wire 34, wires 35 and 36, the signals 2, 2 and wires 37, 38 to terminal C. Armature 24 remains engaged with back contacts 25 as long 60 as any one of the track relays 10, 11 or 12 is de-energized, and thus provision is made for operation of the crossing signals as long as the train approaching the crossing from the left is in any of the sections 3, 4 or 15 65 5. Similar means are provided for causing operation of the crossing signals when a train approaches the crossing from the right. For this purpose a relay 39 similar to relay 9 is controlled by track relays 40, 41 and 42, 70 connected to the respective track sections 6, 7 and 8. So long as none of the track sections 6, 7 or 8 is occupied, relay 39 is energized over the following circuit: from terminal B, through wire 43, front contact 44 and armature 45 of relay 42, front contact 46 and armature 47 of relay 41, wire 48, armature 49 and front contact 50 of relay 40, wire 50', relay 39, and wire 39' to terminal C. When 75 a train approaching the crossing from the right is in any one of the track sections 6, 7 or 8, the circuit through relay 39 is broken and an operating circuit for the signals 2 is established, as follows: from terminal B through wire 51, back contact 52 and armature 53 of relay 54, wire 55, back contact 56 and armature 57 of relay 58, wire 59, back contact 60 and armature 61 of relay 39, wires 62, 34, 35 and 36, signals 2, 2 and wires 37, 38 to terminal C. 80

When a train approaching the crossing from the right passes out of section 6, the circuit through relay 40 is again established, armature 61 is disengaged from back contact 60, and the signal operating circuit is thus 95 100

disrupted. Upon the entry of said train into section 3, the track relay 10 is de-energized, and its armature 20 engages back contact 63. While relay 9 is de-energized, this relay is of the slow-acting type, and its armature 64 remains in engagement with front contact 65 for a sufficient time to permit current to flow from terminal B through the armatures and front contacts of relays 12 and 11, wire 19, armature 20 and back contact 63 of relay 10, wire 66, front contact 65 and armature 64 of relay 9, wire 67, relay 32, and wire 68 to terminal C. Relay 32 is thereby energized and disengages armature 31 from back contact 30, whereby the closing of the operating circuit for the signals 2, 2 is prevented; one branch of said circuit being open at back contact 60 of relay 39 and the other branch at back contact 30 of relay 32. Upon the release of relay 9 at the expiration of its holding time, armature 69 of relay 9 engages back contact 70 and a stick circuit is established through relay 32 by way of terminal B, armature 69 and back contact 70 of relay 9, wire 66, back contact 71 and armature 72 of relay 28, wire 73, front contact 74 and armature 75 of relay 32, wire 67, relay 32, and wire 68 to terminal C. The relay 32 remains energized until relay 9 is again energized, or, in other words, until the train which is receding from the crossing has emerged from track section 5.

Similarly, when a train which approached the crossing from the left passes out of track section 3, relay 9 is again energized and its armature 24 is disengaged from back contact 25, thus opening the signal operating circuit which was established upon the entry of the train into section 5. While the track relay 40 is de-energized upon entry of said train into section 6, thus de-energizing relay 39, the latter, like relay 9, is of the slow acting type, and its armature 76 remains in engagement with front contact 76' a sufficient time to permit current to flow from terminal B through the armatures and front contacts of relays 41 and 42, wire 48, armature 49 and back contact 77 of relay 40, wire 78, front contact 76' and armature 76 of relay 39, wires 79 and 80, relay 58, and wire 81 to terminal C. Relay 58 is thus energized and its armature 57 is disengaged from back contact 36. The establishing of an operating circuit through the signals 2, 2, is thus prevented; one branch of said circuit being open at back contact 25 of relay 9, and the other branch at back contact 56 of relay 58. Upon the release of relay 39 at the expiration of its holding time, armature 116 of said relay engages back contact 117, and a stick circuit through relay 58 is established by way of terminal B, armature 116 and back contact 117 of relay 39, wire 78, back contact 118 and armature 119 of relay 54, wire 120, front contact 121 and

armature 122 of relay 58, wires 79 and 80, relay 58 and wire 81 to terminal C.

It will thus be apparent that provision is made for operation of the signals 2, 2, upon the approach of a train to the crossing A from either direction and for the prevention of operation of said signals as the train recedes from said crossing in either direction.

I have provided means whereby the operation of the crossing signals may be cut out and restarted at will when a train is on either side of the crossing, and whereby furthermore the signals may be set in operation when a train receding from the crossing reverses its direction and approaches said crossing.

When, for example, a train approaching the crossing from the left stops at station D and it is desired to discontinue temporarily the operation of the crossing signals, a push button 82 is momentarily depressed, establishing a flow of current from terminal B through contact 83, push button contact 84, wire 85, relay 86, wire 87, armature 88 and back contact 89 of relay 9 (which was de-energized by the approach of said train) wire 90, relay 28, and wire 91 to terminal C. Relay 28 is thus energized and the signal operating circuit is disrupted by the disengagement of armature 27 from back contact 26 of said relay. Energization of relay 86 causes armature 92 of said relay to engage contact 93, whereby a stick circuit is established through relays 86 and 28 from terminal B through the normally engaged contacts 94 and 95, wire 97, front contact 93 and armature 92 of relay 86, wire 85 and thence as before through relays 86 and 28. Thus, said relays 86 and 28 remain energized notwithstanding the release of push button 82. Now, when a train is about to proceed from the station D across the crossing A, the push button 96 is momentarily depressed, disengaging contact 95 from contact 94 and breaking the circuit through relays 86 and 28, whereby contact 26 is again engaged by armature 27 of relay 28 and the operating circuit for the signals 2, 2 is again established.

Should the train recede from the station after push button 82 has been depressed to discontinue operation of the crossing signals, the circuit through relays 86 and 28 will be broken upon energization of relay 9 and consequent disengagement of armature 88 from contact 89, and the signal controlling circuit is thus automatically restored to normal condition. Similarly, if after button 82 has been depressed the operator should neglect to depress button 96 and the train should proceed across the crossing, the picking up of relay 9 de-energizes relays 86 and 28 and the signal controlling circuit is automatically restored to normal.

In case a train approaching the crossing from the right stops in section 6 before reaching the crossing, and it is desired to discon-

tinue temporarily the operation of the crossing signals, push button 99 is momentarily depressed to engage contact 100 with contact 101. Current now flows from terminal B through contacts 101 and 100, wire 102, relay 103, wire 104, armature 105 and back contact 106 of relay 39 (which was de-energized by the approach of said train), wire 107, relay 54, and wire 108 to terminal C. Relays 103 and 54 are thus energized; the energization of relay 54 disengaging armature 53 from back contact 52 and thus breaking the operating circuit for the signals 2, 2. Energization of relay 103 engages armature 109 with contact 110 and thus closes a stick circuit through relays 103 and 54 from terminal B, through normally closed contacts 111, 112, wire 113, front contact 110 and armature 109 of relay 103, wire 114 and wire 102 and thence as before through relays 103 and 54; whereby said relays 103 and 54 remain energized notwithstanding release of push button 99. When the train which halted in section 6 is about to proceed across the crossing A, the push button 115 is operated to disengage contact 112 from contact 111, whereby relays 103 and 54 are de-energized, armature 53 is re-engaged with contact 51, and the signal operating circuit is again established. Since the engagement of armature 105 with contact 106 of relay 39 is a prerequisite to energization of relays 54 and 103, it will be evident that said relays will be automatically de-energized and the signal controlling circuit restored to normal should the train which halted in section 6 proceed across the crossing without depression of button 111, or if said train, instead of proceeding across the crossing, should recede a sufficient distance from the crossing to cause relay 39 to be de-energized.

It has been noted that when a train proceeding from the right is receding from the crossing A in section 3, the relay 32 is energized and prevents the operation of the crossing signals. Through my invention, the crossing signals may be readily set in operation if it is desired that the train occupying section 3 should reverse its receding movement and approach the crossing. This is accomplished by momentarily depressing first the push button 82 and then the push button 96. Depression of push button 82 energizes relays 86 and 28 as previously described. The energization of relay 28 disengages armature 72 from contact 71 and thus breaks the stick circuit which was established through relay 32 pursuant to the entry of the train into section 3. Relay 32 is thus de-energized and its armature 31 is engaged with back contact 30. Upon then momentarily depressing push button 96, the operator de-energizes the relays 86 and 28; the de-energization of relay 28 resulting in engagement of back contact 26 by armature 27. Since ar-

mature 27 now engages back contact 26 and armature 31 of relay 32 is engaged with back contact 30, it will be apparent that an operating circuit is established through the signals 2, 2; the track relay 10 and thus the relay 9 having been de-energized by the entry of the train into section 3, and armature 24 being thus in engagement with back contact 25.

Likewise, should it be desired that a train receding from the crossing in section 6 reverse its travel and approach said crossing, the signals 2, 2, may be set in action by successive momentary depression of push buttons 99 and 115. Depression of push button 99 energizes relays 103 and 54; the energization of relay 54 breaking the stick circuit through relay 58 by disengaging armature 119 from contact 118, and thus de-energizing said relay 58 whereby armature 57 is engaged with contact 56. Depression of button 115 de-energizes relays 103 and 54, armature 53 of relay 54 returning into engagement with contact 52. The crossing signal circuit is thus established, armature 61 of relay 39 having engaged back contact 60 in response to the entry of the train into section 6.

Means are provided for indicating to the attendant whether or not the signal control circuits are manually cut out. For this purpose, relay 86 is provided with an armature 125 which engages back contact 126 so long as relay 86 is de-energized. At such time current flows from terminal B through said armature and back contact, wire 127, light 130, and wire 131 to terminal C. When relay 86 is energized current from terminal B flows through armature 125, front contact 132, wire 133, and light 134 to terminal C. Light 130 may be conveniently colored green and light 134 red. The attendant is thus continuously apprised of the condition of the manual control circuit associated with relay 86. Similarly relay 103 has an armature 135 engageable with either back contact 136 or front contact 137 to thereby cause current to flow through either of the differently colored lights 138, 139 and thus indicate the condition of the manual control circuit associated with said relay 103.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. In apparatus for the control of a highway signal at a railway crossing, a section of railway track, a track relay connected to the rails adjacent one end of said section, a crossing signal control relay controlled by said track relay for causing operation of the sig-

nal during approach of a train to the crossing, means comprising a relay controlled by said crossing signal control relay for causing cessation of operation of the signal in response to recession of said train from the crossing through said section, and means comprising a manually controlled relay for causing cessation of operation of said signal at the will of an operator.

10. 2. In apparatus for the control of a highway signal at a railway crossing, a section of railway track, a normally energized relay, means whereby said relay is de-energized upon the entry of a train into said section, a second relay controlled by the first mentioned relay, a manually controlled relay, and connections comprising contacts of the respective relays for causing operation of said signal.

15. 3. In apparatus for the control of a highway signal at a railway crossing, a section of railway track, a normally energized slow-acting relay, means whereby said relay is de-energized upon the entry of a train into said section, a relay controlled by the first mentioned relay, a manually controlled relay, and connections comprising contacts of the respective relays for causing operation of said signal.

20. 4. In apparatus for the control of a highway signal at a railway crossing, a section of railway track, a normally energized slow-acting relay, means including a track relay whereby said slow-acting relay is de-energized upon entry of a train into said section, a second relay controlled by a front contact of said slow-acting relay, a manually controlled relay; and a circuit including a back contact of said slow-acting relay, a back contact of said second relay, and a back contact 25 of said manually controlled relay, for causing operation of said signal.

40. 5. In apparatus for the control of a highway signal at a railway crossing, a series of sections of railway track each provided with a track relay, a slow-acting relay controlled by said track relays, an auxiliary relay controlled by said slow-acting relay for energization in response to entry of a train from a given direction into one of said sections, a stick circuit for said auxiliary relay; a manually operable relay, and connections dependent upon de-energization of said slow-acting relay, said auxiliary relay, and said manually operable relay for causing operation 45 of the crossing signal.

50. 6. In apparatus for the control of a highway signal, at a railway crossing, a series of sections of railway track each provided with a track relay, a slow-acting relay controlled by the track relays for said sections, an auxiliary relay controlled by said slow-acting relay for energization in response to entry of a train from a given direction into one of said sections, a stick circuit for said auxiliary relay controlled by said slow-acting

relay; a manually operable relay; and means operating upon de-energization of said slow-acting relay, said auxiliary relay, and said manually operable relay for causing operation of the crossing signal, said manually operable relay having means controlling said stick circuit.

7. In apparatus for the control of a highway signal at a railway crossing, a series of sections of railway track each provided with a track relay, a slow-acting relay controlled by the track relays for said section, an auxiliary relay controlled by a front contact of the slow-acting relay for energization in response to entry of a train from a given direction into one of said sections, a stick circuit for said auxiliary relay, a manually operable relay; means operating upon de-energization of said slow-acting relay, said auxiliary relay and said manually operable relay for causing operation of the crossing signal; said manually operable relay having means controlling said stick circuit, and means comprising contacts controlled by said slow-acting relay for controlling the energization of said manually operable relay.

8. In apparatus for the control of a highway signal at a railway crossing, a section of railway track, means comprising a relay responsive to entry of a train into said section for causing operation of a crossing signal, means comprising a relay controlled by the first mentioned relay for preventing operation of the signal in response to recession of a train from the crossing in said section, and manually operable means for controlling the second mentioned relay to cause operation of the signal in the event of reversal of said receding movement.

9. In apparatus for the control of a highway signal at a railway crossing, a section of railway track, a first relay, means controlled by said first relay for causing operation of a crossing signal, means comprising a track relay responsive to the entry of a train into said section for controlling said first relay, a manually controllable relay, means controlled thereby for rendering said first mentioned means ineffective, and means controlled by said first relay for preventing operation of said manually controllable relay.

10. In apparatus for the control of a highway signal at a railway crossing, a section of railway track, a first relay, means controlled by said first relay for causing operation of a crossing signal, means comprising a track relay responsive to the entry of a train into said section for controlling said first relay, means comprising a second relay controlled by said first relay for preventing operation of the crossing signal when a train recedes from the crossing in said section, manual control means comprising a third relay for preventing operation of the crossing signal.

at the will of an operator, and connections controlled by said third relay for throwing out of action said second relay.

11. In apparatus for the control of a highway signal at a railway crossing, a section of railway track, a first relay, connections controlled by said first relay for causing operation of a crossing signal, means comprising a track relay responsive to the entry of a train into said section for controlling said first relay, means comprising a second relay controlled by said first relay for preventing operation of the crossing signal when a train recedes from the crossing in said section, manual control means comprising a third relay for preventing operation of the crossing signal at the will of an operator, connections controlled by said third relay for throwing out of action said second relay, and manual means for de-energizing said third relay.

12. In apparatus for the control of a highway signal at a railway crossing, a section of railway track, a first relay, connections controlled by said first relay for causing operation of a crossing signal, means comprising a track relay responsive to the entry of a train into said section for controlling said first relay, means comprising a second relay controlled by said first relay for preventing operation of the crossing signal when a train recedes from the crossing in said section, manual control means comprising a third relay for preventing operation of the crossing signal at the will of an operator, connections controlled by said third relay for throwing out of action said second relay, and means for de-energizing said third relay either manually or automatically.

13. In apparatus for the control of a highway signal at a railway crossing, a section of railway track, a first relay, connections controlled by said first relay for causing operation of a crossing signal, means comprising a track relay responsive to the entry of a train into said section for controlling said first relay, manual control means for rendering said first relay ineffective to control said signal, and means for indicating to an attendant whether the manual control means is in or out of action.

14. In apparatus for the control of a highway signal at a railway crossing, a section of railway track, a slow-acting relay, connections controlled by said relay for causing operation of a crossing signal, means comprising a track relay responsive to the entry of a train into said section for controlling said slow-acting relay, means comprising a third relay energized over contacts controlled by said slow-acting relay for preventing operation of the crossing signal when a train recedes from the crossing in said section, a stick circuit for said third relay, a manually controllable relay having contacts controlling

both the connections for causing operation of said signal and said stick circuit, means comprising a manually operable element for energizing said manually controllable relay to thereby disrupt both said connections, and means comprising a second manually operable element for causing said manually controllable relay to be de-energized.

15. In combination, a section of railway track, a track relay for said section, a slow acting relay, a circuit for said slow acting relay, including a front contact of said track relay, a stick relay, an auxiliary relay, a pick up circuit for said stick relay including a back contact of said track relay and a front contact of said slow acting relay, a stick circuit for said stick relay including back contacts of said slow acting relay and said auxiliary relay and a front contact of the stick relay, a manually controlled circuit for said auxiliary relay, and a signal controlled by said slow acting relay, by said stick relay, and by said auxiliary relay.

16. In combination, a section of railway track, a track relay for said section, a slow acting relay, a circuit for said slow acting relay including a front contact of said track relay, a stick relay, an auxiliary relay, a pick up circuit for said stick relay including a back contact of said track relay and a front contact of said slow acting relay, a stick circuit for said stick relay including back contacts of said slow acting relay and said auxiliary relay and a front contact of the stick relay, a manually controlled circuit for said auxiliary relay, a signal; and an operating circuit for said signal including back contacts of said slow acting relay, said stick relay, and said auxiliary relay.

17. In combination, a section of railway track, a track relay for said section, a slow acting relay, a circuit for said slow acting relay including a front contact of said track relay, a stick relay, an auxiliary relay, a pick up circuit for said stick relay including a back contact of said track relay and a front contact of said slow acting relay, a stick circuit for said stick relay including back contacts of said slow acting relay and said auxiliary relay and a front contact of the stick relay, a manually controlled circuit for said auxiliary relay including a back contact of said slow acting relay; and a signal controlled by said slow acting relay, by said stick relay, and by said auxiliary relay.

18. In combination, a section of railway track, a track relay for said section, a slow acting relay, a circuit for said slow acting relay including a front contact of said track relay, a stick relay, an auxiliary relay, a pick up circuit for said stick relay including a back contact of said track relay and a front contact of said slow acting relay, a stick circuit for said stick relay including back contacts of said slow acting relay and said auxiliary re-

lay and a front contact of the stick relay, an additional relay, two manually operable push buttons; a pickup circuit for said auxiliary relay and said additional relay in series controlled by one of said manually operable push buttons, a branch for said pickup circuit around said one push button controlled by the other said push button and including a front contact of said additional relay; and a signal controlled by said slow acting relay by said stick relay, and by said auxiliary relay.

In testimony whereof, I have signed my name to this specification this 8th day of September, 1930.

EARL M. ALLEN.
